FIG. 5

INVENTOR
THOMAS L. RYAN
By *P. M. Hunt*
ATTORNEY.

UNITED STATES PATENT OFFICE.

THOMAS L. RYAN, OF MUNCIE, INDIANA.

DISTRIBUTOR STAND.

Application filed September 8, 1921. Serial No. 499,357.

To all whom it may concern:

Be it known that I, THOMAS L. RYAN, a citizen of the United States, residing at Muncie, in the county of Delaware and State 5 of Indiana, have invented certain new and useful Improvements in Distributor Stands, of which the following is a specification.

This invention relates to improvements in electric appliances. In this specification 10 the invention is referred to as a distributor stand, and it is equipped with a standard Edison bulb.

The object of the invention is to provide an appliance of this character which is economical in construction and is capable of being economically finished and of being equipped in divers ways making easy the use of many different types or standardized electrical appliances such as electric light 15 bulbs, electric light regulators and dimmers, attachment plugs, extension columns or candles and current taps.

In the construction and use of appliances of the class above referred to, namely,—a 20 combination of a stand and a socket,—as such devices have been hitherto constructed, it is necessary to use a standard complete electric socket, comprising the usual porcelain and metal interior parts, the fiber 25 insulating sleeve, and the metal outer shell. In the present invention such construction is provided that the metal outer shell may be dispensed with.

Other important features of utility will 30 be apparent as the nature of my invention is understood in reading the specification.

The objects of this invention are accomplished by, and the invention is embodied in the new construction combination and arrangement of parts described in the following specification and illustrated in the accompanying drawings. The invention is defined in the appended claims.

In the drawings, suitable characters of 35 references are applied to the different parts of the invention as they appear in the several views, in which—

Figure 1 is a side view of the distributor stand, fitted with a standard electric bulb.

Figure 2 is a top plan view.

Figure 3 is a vertical central sectional view of the stand.

Figure 4 is a bottom plan view.

Figure 5 is a horizontal sectional plan 55 view taken on the line 5—5 in Figure 3.

Figure 6 is a vertical central sectional view showing the several interior parts assembled.

Figure 7 is a central sectional view showing the arrangement of a modified form of 60 standard electric socket and

Figure 8 is an ensmalled view of the distributor stand equipped with a current tap.

This distributor or lamp stand may be made of sheet metal, or of composition, or 65 preferably, of cast metal such as iron, brass or white metal. It has a flared bottom or base portion as shown, and is of hollow construction. The body walls A are of suitable curvature, their upper portions B being 70 parallel and forming a cylindrical cavity C, the function of which will be presently referred to. The outer surface of the stand may be of plain contour, or may be provided with a suitable decoration. Also it will be 75 understood that the stand may be polygonal in cross section. The diameter of the cavity C is slightly greater than the outside diameter of the fiber insulatory sleeve of a standard electric socket. The opening D of 80 the said cavity is of suitable diameter to permit the insertion therethrough of a socket and its fiber sleeve.

Formed integral with the inner side of 85 wall B are lugs E, preferably three in number. Each of these lugs may be provided with a stud portion E¹ which facilitates the retention of the socket sleeve at central position and provides a seating for the said sleeve at which it may be retained securely 90 in position. At a suitable distance from the bottom of the stand body, are the integrally formed lugs F. These lugs have the recesses F¹ and their extent toward each other is such as to provide a space between 95 them to accommodate a connecting element presently to be referred to.

The simplicity of construction of this stand is readily apparent. It is capable of being cast economically and in quantity, 100 and little, if any, machine work is required to make the casting ready to receive the interior parts. In completing the stand as an article of manufacture, the external surface of the stand is smoothed or polished 105 and then treated to a coat of enamel or electroplating or other finishing materials. The work of assembling of the electrical parts is very simple. The preferred form of socket to be used in this stand is that 110

shown in Figure 6, and in which the parts are contained in a cylindrical sleeve 1 made of fiber or other suitable insulatory material. A socket of this type has the usual terminals 2 and 2, and an arm 3 having its end bent at an angle and being provided with an eye that is internally threaded, and which eye may be disposed at position substantially central of the stand.

10 In assembling, the socket, provided with the usual insulated parallel cord 4 having its wires connected to the terminals 2 and 2, is simply inserted in the cavity C; the lower edge of the sleeve 1 resting on the lugs E and at registration with the studs E¹. The cord 4 is then passed through the hole A¹ and at its free end is connected a standard attachment plug (not shown).

20 A rod 6 each end of which is threaded constitutes a connecting member between the socket and the stand, its upper end being screwed into the eye of the arm 3. The lower end of the rod 6 occupies position in the space between the lugs F, so that when 25 the nut 7 is screwed on the lower end of the rod, and against the lugs F, the sleeve or fiber body shell of the socket is drawn to and retained at tight engagement with the seats therefor provided by the lugs E. The 30 socket so disposed and retained constitutes a receptacle into which the base of any standard electric lamp or plug attachment may be screwed.

35 In the modification shown at Figure 7 is shown the adaptation of the stand to the use of a socket switch of the class comprising the key-socket type. In this adaptation the key shaft 8 is detachable and is inserted through a suitable hole 10 in the wall B. 40 In the use of this type of electric socket the opening D is of diameter sufficient to permit the insertion of the fiber sleeve 9. To adapt the stand to accommodate a standard key socket, or a push through type of socket, in 45 which the key shaft or push studs respectively are not detachable, vertical openings in the walls B are provided so that the socket may be lowered to the position shown.

By this invention the standard electric 50 base connection C¹ is available as substantially an integral part of the stand. A feature of importance is that the head or top portion of the stand constitutes the other shell or housing for the fiber sleeve and is 55 adapted to decorative adornment in keeping with the contour and design of the stand proper. The socket so provided is not only easily available for the application to use of the electric bulb solely as a lighting device, as shown in Figure 1, but is available 60 and of utility for the application to use of electric current regulators or dimmers so that a table lamp capable of varied degrees of illumination is afforded. By the use of 65 a column type extension a lamp stand of

candelabra effect is had. Variation of the height of the lamp stand may be had by altering the length of same between the head portion and the bottom so that the construction and combination of the interior parts 70 is unaffected, and at the same time symmetry in design may be maintained and in harmony with the use of various styles of shades to be supported by the electric bulb, comprising shades made of parchment, silk 75 or of glass.

By the application of a plug of the current-tap type, as shown in Figure 8, there may be light from the bulb, and the current may be delivered also to one or more electric appliances. With the rapidly increasing use of electric appliances, such as the electric iron, grill, toaster, sweeper, fan, heater, and other devices too numerous to mention, the utility of having a stand from 80 which distribution of the electric current may be had from desirable locations, is easily apparent.

With the attachment plug of the cord 4 applied to the electric current source, either 90 in a lighting fixture, or at an outlet at the wall, or the base-board, or other suitable place, the distributor stand may be disposed at a desirable location with reference to the worker's needs for illumination or power. 95

Where illumination directly from the distributor stand is not desired, a multiple outlet plug of any standard make may be used, thereby making possible the connecting up 100 for simultaneous use a number of electric appliances.

What I claim as my invention, and desire to secure by Letters Patent, is

1. In an electric distributor stand, a shell having a base and an electric socket-receiving cavity adjacent the upper end of the shell opening through said upper end, a series of lugs in the shell at the bottom of the cavity having approximately L-shaped seats in their upper sides, opposed base lugs in the shell below the first named lugs, an electric socket in the cavity seated in the seats of the first named lugs, a depending arm carried by the socket and having a threaded aperture aligned with the space between the base lugs, a rod having threaded ends one of which is engaged in the aperture of the arm and the other of which passes through the space between the base lugs, and a nut on the last named rod end engaged with and beneath the 110 base lugs.

2. In an electric distributor stand, a shell having a base and an open top, lugs in the open top integral with the shell, an electric socket in the open top seated on the lugs and having a depending arm with a threaded aperture, base lugs in the shell integral therewith and spaced below the first named lugs, said base lugs being spaced apart, a rod 125 threaded into the aperture of the arm and 130

extending through the space between the base lugs, and a nut threaded on the rod and engaged with and beneath the base lugs.

3. In an electric distributor stand, a cast shell having a base formed to seat on a supporting surface so as to hold the shell in a vertical position and having an open top, a seat cast integral with the shell and located within the open top, an electric socket, said top being formed of a diameter to conformably receive the electric socket therein so as to allow the socket to directly engage on and with the seat, spaced abutment members cast

integral with the shell and located above and adjacent to the base, a rod threaded at its lower end, means to connect the upper end of the rod to the electric socket so as to allow the rod and the socket to be placed in position in the shell and the threaded end of the rod passed through the space between the members, and a nut on the threaded end of the rod engaged with said members to hold the parts in their aforementioned positions.

In testimony whereof I affix my signature.

THOMAS L. RYAN.
